(57) **CLAIM**

The ornamental design for a footboard, as shown and described.

DESCRIPTION

FIG. 1 is a front perspective view of a footboard for a medical bed embodying my design.

FIG. 2 is a rear perspective view thereof.

FIG. 3 is a front view thereof.

FIG. 4 is a rear view thereof.

FIG. 5 is a top plan view thereof.

FIG. 6 is a bottom plan view thereof; and,

FIG. 7 is a right side elevational view with the left side being a mirror image thereof.

The broken line in FIGS. 1-4, 6 and 7 forms no part of the claimed design.

1 Claim, 4 Drawing Sheets

FIG. 1

FIG. 2

FIG. 5

FIG. 6

FIG. 7
